[57] ABSTRACT

A resettable latch mechanism for holding an operating member, the release of which causes the closing of a fire damper, smoke hatch, fire door or the like, when an electrical circuit connected thereto is energized. The latch mechanism has a latch plate and a latch element cooperating with the latch plate, either the latch plate or the latch element being a movable member, and an actuator adapted to move the movable member responsive to energization of the electrical circuit.

FIG. 2.

FIG. 3.

FIG. 4.

LATCH MECHANISM FOR FIRE AND SMOKE DAMPERS AND THE LIKE

The present invention generally relates to fire, smoke and blast dampers or hatches and, more particularly, to latch mechanisms for automatically closing such devices responsive to detection of conditions which indicate the existence of a fire, excessive smoke or an impending blast condition.

Since heating and ventilation ducts as well as other air corridors in buildings may be required to have dampers, hatches or doors which will be automatically closed when excessive smoke is present or when a fire breaks out, it is desirable to have a latch mechanism for operating such dampers or hatches if either condition is present. Latching mechanisms that are electrically actuated by either smoke or fire detectors are conveniently used, since either of these conditions will result in the dampers and hatches being closed which may not be done from only mechanical temperature responsive devices.

Release mechanisms typically include fusible links which can be actuated by a small electrical charge to release a smoke damper or the like for closing when a system detects excessive smoke or a fire or an impending blast condition. One disadvantage of such fusible links is that they are essentially one-use devices and must be replaced after they are actuated. It should be apparent that a large building may include a considerable number of dampers, fire doors and hatches and would thereby utilize a significant number of such fusible links. In the event there is a malfunction within the system which triggers their actuation, considerable expense may be experienced in replacing all of the links. Additionally, while their reliability is often stated to be quite high, it is unknown whether a particular fusible link will operate until it is in fact actuated and, once this is confirmed, it is necessary to replace the very fusible link that was actuated.

Accordingly, it is an important object of the present invention to provide a latch mechanism that may be used in conjunction with fire dampers, smoke hatches, fire doors and the like in a system and which is actuatable responsive to the energization of an electrical circuit, but which is reusable in the sense that it does not require the replacement of components after it has been actuated.

A related object is to provide a latch mechanism which may be placed in a cocked or ready condition and which will thereafter release and close a fire damper, smoke hatch or the like responsive to energization of an electrical circuit and which may be thereafter returned to its ready condition by a relatively simple manipulation of the mechanism.

Still another object of the present invention lies in the provision for producing a latch mechanism having the above advantages from a relatively small number of components and thereby insure low manufacturing costs.

Yet another object of the present invention is to provide a release mechanism having the above advantages which, because of its design and construction, may be tested in the actual environment in which it is to work, and thereby provide definite assurance that the system will achieve its intended purpose. A closely related object lies in the provision for enabling such testing without incurring any expense in terms of replacing any

components within the mechanism to return it to a ready condition.

Other objects and advantages will become apparent from the following detailed description, while referring to the attached drawings, in which:

FIG. 1 is a side elevation of an actuator and latch mechanism embodying the present invention, shown in ready condition together with an operating member the release of which will cause the closing of a fire damper, smoke hatch or the like;

FIG. 2 is a section taken generally along the line 2-2 of FIG. 1;

FIG. 3 is a side elevation of the mechanism shown in FIG. 1, particularly illustrating the latching mechanism in its released condition; and

FIG. 4 is a side elevation of an alternative construction also embodying the present invention and is illustrated in a ready condition.

While the present invention will be described in connection with certain preferred embodiments, it should be understood that it is not intended to limit the invention to these particular embodiments. On the contrary, it is intended to cover all alternatives, modifications and equivalents as may be included within the spirit and scope of the invention as expressed in the appended claims.

Turning now to the drawings and particularly FIGS. 1-3, a latch mechanism, indicated generally at 10, is shown together with a flexible link, which in the illustrated drawings is shown to be chain 12 adapted to operate a fire damper, fire door, smoke hatch or the like (not shown). The chain 12 is held by the latch mechanism 10 so that when the mechanism releases the chain, it will cause the damper or hatch to close and confine smoke or fire to a local area and thereby prevent rapid spreading through a heating and ventilating duct, for example, as well as other corridors in which such dampers and hatches are positioned.

The latch mechanism 10 embodying the present invention is adapted to release the chain 12 responsive to the energization of an electrical circuit which is not shown except for electrical lines 14 that terminate in the illustrated latch mechanism. It is intended however, that the latch mechanism 10 be a part of an overall system that incorporates smoke detectors, fire detectors as well as devices which would detect an impending blast condition and in the event any one of these detectors would be actuated, would energize an electrical circuit that would result in current flowing through lines 14 to actuate the latch mechanism embodying the present invention.

The embodiment shown in FIGS. 1-3 includes a generally horizontal frame 16 having an upturned end portion 18 and an electrically activated actuator 20 having a movable piston 22 for contacting a side portion 24 of a generally U-shaped member, indicated generally at 26, which also has a middle portion 28 and a second side portion 30. The U-shaped member 26 includes generally horizontal elongated slots 32 in each side portion thereof through which the frame 16 may pass, so that the U-shaped member 26 is movable relative to the frame and is thereby responsive to the action of the piston 22 of the actuator 20. A spring 34 is interposed between the upturned end portion 18 of the frame and the side portion 30 of the U-shaped member to normally bias the U-shaped member toward the position shown in FIG. 1 wherein the latch mechanism is in a cocked

or ready condition. A stop 36 may be provided to limit the leftward movement of the U-shaped member 26. In operation, energization of the electrical circuit through lines 14 will cause the piston 22 of the actuator 20 to move toward the right and will move the latch plate 26 to the right and compress the spring 34 all as shown in FIG. 3.

The actuator 20 may be of many different constructions. For example, the electrical line 14 may be continuous through a heating coil contained within the actuator for heating a heat expandable material or fluid which, when it is expanded, will force the piston 22 to the right as previously described. This type of actuator has an inherent advantage in that a time delay is experienced before the chain is released due to the fact that it requires some period of time before the heating coil will cause sufficient expansion of the material to move the piston 22 through a distance that will cause the release of the chain. However, it should be understood that other devices such as solenoids or the like may be conveniently used, and if such devices act instantaneously, conventional electrical or electromechanical delay devices may be incorporated within the system if some delay period is desired. In this connection, it is preferred that the operation of the mechanism be delayed for a short period so that any transient electrical signals or inadvertent energization of the system by persons within a building incorporating such a system will not actuate all of the release mechanisms therein.

To release the chain 12, the mechanism embodying the present invention includes a latch element, indicated generally at 40, which cooperates with a latch plate 42 carried by the U-shaped member 26 so as to be movable therewith. The latch element 40 includes an elongated member 44 shown to be one end of a wire spring that is wrapped around a screw 46 mounted to a bracket 48 which is secured to the frame 16, the other free end 50 of the wire spring contacting the underside of the frame 16. Thus, the free end 44 of the wire spring is biased in a downward direction as shown. It should be understood that the elongated member need not, in and of itself, be a part of a wire spring, but may have a separate spring or the like acting upon a nonresilient member.

The latch member 40 is held in position by the latch plate 42 which is suitably secured to the middle portion 28 of the U-shaped member and has a suitable slot 52 adapted to receive the elongated member 44 as is shown in FIG. 2. Thus, the chain is held by the elongated member when the latch plate 42 is in the position shown in FIG. 1 and is adapted to release the chain as the piston 22 moves the U-shaped member 26 to the right so that the latch plate 42 moves away from the elongated member a sufficient distance to release the chain as is shown in FIG. 3.

To return the latch mechanism to its ready or cocked position, the latch plate 42 is moved back to the position shown in FIG. 1, the chain is placed upon the elongated member 44 and it is then only necessary to insert the elongated member into the slot as best shown in FIG. 2. It is preferred that the elongated member 44 be downwardly inclined so that the chain will bear against the latch plate 42 and will be free to drop when the latch element 40 is released by the movement of the latch plate 42. While the embodiment illustrated shows the elongated member being attached to the frame 16

and the latch plate 42 being movable relative thereto, it should also be realized that the latch plate could be fixed to the frame 16 and that the latch member be mounted upon the U-shaped member 26 for movement. Moreover, while the actuator 20 is specifically described as having its piston 22 extendable responsive to energization of the electrical circuit, an actuator could be utilized wherein the piston is normally extended with the energization of the electrical circuit, and responsive to deenergization thereof cause retraction of the piston 22. With such an arrangement, the actuator 20 may be positioned where the spring 34 is shown so that the piston would be attached to and be adapted to pull the side 30 of the U-shaped member 26 to the right. The spring 34 may then be adjacent the actuator 20 or may be placed where the actuator is positioned in FIG. 1 but placed in a tensioned condition rather than a compressed condition as specifically shown in FIG. 3 so that it would bias the U-shaped member to the left in either case.

Turning now to the alternative construction also embodying the present invention and shown in FIG. 4, a frame 60 having a downwardly turned end portion 62 is provided, with the end portion 62 providing a mounting surface for an actuator which is shown to be an electromagnet 64 connected to the electrical circuit through lines 66. The mechanism includes a latch element, indicated generally at 68, and similar to the previously described latch element 40 shown in FIG. 1, and accordingly has an elongated member 70 also comprising one free end of a wire spring which is wrapped around a screw 72 or the like, the other end 74 of which bears against the underside of the frame 60. The screw is attached to a support bracket 76 that is attached to the frame 60.

To hold the latch element 68, a pivotable, ferromagnetic latch plate 80 is provided and has a slot substantially similar to the slot 52 shown in FIG. 2. The upper end of the latch plate 80 has a perpendicularly bent portion 82 which bears against the underside of the frame 60 to limit the leftward movement of the lower portion of the latch plate 80 to the position shown. This prevents the latch plate from moving out of the immediate proximity and working range of the electromagnet 64. The pivotable latch plate is mounted to the frame 60 by means of a pin 84 or the like journaled by a pair of downwardly extending ears 86 (only one of which is shown) that are attached to or integrally formed with the frame 60. Thus, the lower portion of the latch plate 80 is free to move to the right shown in phantom.

In operation, energization of the electromagnet 64 will pull the latch plate to the right and release the latch member 68 enabling the chain 12 to drop and cause a fire damper, smoke hatch or the like to be closed. It should also be understood that the actuator may also be a solenoid device which is positively mechanically connected to the latch member so that when it is energized, it will positively pull the latch plate to the position shown in phantom and release the latch element. In the event such an actuator is used with a mechanical connection, the latch plate need not be produced from a ferromagnetic material. It is also contemplated that a solenoid device having a mechanical connection may be used wherein it is adapted to retract and pivot the latch plate to the position shown in phantom responsive to the deenergization of the electrical circuit if desired.

To return the mechanism to its cocked or ready condition, the chain is merely replaced on the elongated member 70 and the elongated member is inserted into the slot in the manner as previously described with respect to the embodiment shown in FIGS. 1-3.

The elongated member 70 is preferably in a downwardly inclined position as shown so that a component of force is exerted to the left by virtue of the downward bias of the elongated member 70. This has the effect of holding the latch 80 in the position shown so that its portion 82 bears against the frame 60. By virtue of this leftward component of force, no other spring or biasing means is required to hold the latch plate in its latched or ready position.

Thus, the invention described herein represents a marked improvement over existing devices for causing fire dampers and hatches to close and has many desirable attributes in terms of the ability to actually test the system. The cost of maintenance of a system incorporating the latch mechanisms embodying the present invention is reduced since they are capable of being reused by merely returning them to their ready condition without additional expense. The invention described herein is believed to satisfy all of the objects that have been previously set forth.

I claim as my invention:

1. A latch mechanism for a fire damper, smoke hatch, fire door or the like actuatable responsive to the energization of an electrical circuit, the combination comprising:

a frame,
a latch plate, support member slidable on frame and carrying said latch plate;
a latch element mounted on the frame and cooperating with said latch plate, said latch element being held by said latch plate in latched position;
said latch plate and latch element being movable members;
spring means for resiliently holding one movable member in latched position;
an actuator fixed to the frame and having an extendable piston for contacting said support member so that extension of said piston moves said support member and latch plate away from said latch element to release said latch element responsive to the energization of the electrical circuit.

2. A latch mechanism as defined in claim 1 wherein said spring means is interposed between a portion of said frame and said support member, the spring having sufficient force to return said piston to its unextended position when said circuit is deenergized.

3. A latch mechanism for a fire damper, smoke hatch, fire door or the like actuatable responsive to the energization of an electrical circuit, the combination comprising:

a frame,
a latch plate mounted on the frame;
a latch element mounted on the frame and cooperating with said latch plate, said latch element includ-

ing an elongated member operably connected to said frame and extending to and being retained by said latch plate when in latched condition; said latch plate and latch element being movable members;

spring means normally biasing said elongated member in a downward direction, said elongated member being inclined at an acute angle relative to said latch plate such that said elongated member exerts a force upon said latch plate in a direction toward said latch element to hold said latch plate in latched condition;

an actuator fixed to the frame for moving said latch plate away from said elongated member to release the same responsive to energization of the electrical circuit.

4. A latch mechanism as defined in claim 3 wherein said latch plate includes a slot having a retention surface to permit the insertion and retention of said elongated member therein.

5. A latch mechanism as defined in claim 3 wherein said elongated member comprises one free end of a wire spring wrapped around a pin, the other free end of which contacts the underside of said frame so as to normally bias said elongated member in a downward direction so that upon release thereof by said latch plate, said elongated member will move downwardly away from said latch plate.

6. A latch mechanism as defined in claim 3 wherein said latch plate is pivotally mounted upon said frame, the lower end portion of the latch plate including a slot having a retention surface for holding said elongated member, said actuator being located adjacent said latch plate and adapted to pivot said latch plate when said electrical circuit is energized, said pivoting movement of the latch plate releasing the elongated member.

7. A latch mechanism for a fire damper, smoke hatch, fire door or the like actuatable responsive to the energization of an electrical circuit, the combination comprising:

a frame,
a latch plate movably mounted on the frame;
a latch element comprising a wire spring wrapped around a pin, one free end of said spring cooperating with said latch plate and being held by said latch plate in latched position, the other free end of said spring contacting the underside of said frame so as to normally bias said free end of said spring in a downward direction so that upon release thereof by said latch plate, said free end of said wire spring will move downwardly away from said latch plate; and

an actuator fixed to the frame and adapted to move said latch plate to release said free end of said wire spring responsive to the energization of the electrical circuit.
